MIXING OR DISSOLVING APPARATUS, ETC

Gordon MacLean, Flushing, N. Y., assignor to
 The Turbo-Mixer Corporation, New York, N. Y.,
 a corporation of New York

Application July 31, 1937, Serial No. 156,664

2 Claims. (Cl. 259—107)

This invention relates to mixing apparatus and to dissolving apparatus. It is particularly applicable to mixing or dissolving tanks in which liquid is repeatedly recirculated by one or more rotating impellers, each of which discharges the liquid outwardly in tangential or quasi-tangential directions.

When such a rotating impeller acts on liquid of low viscosity in a plain cylindrical tank, the rotary motion of the impeller is imparted to the mass of liquid. The liquid swirls and a vortex forms over the impeller. Thus, the mixing action is poor, since the whole mass of liquid tends to move as a unit, with the elemental volumes travelling in nearly circular paths.

With a very viscous liquid the drag of the tank wall on the liquid largely counteracts the tendency of the entire mass to swirl. The vortex is relatively small. The elemental volumes of the liquid are drawn inwardly by the impeller, in pronounced spiral paths, and the mixing action is satisfactory. To obtain similar mixing action with a liquid of low viscosity, it is usual to place baffles on the tank wall for the purpose of establishing the necessary drag between the tank and the mass of liquid. As the viscosity of the liquid increases, the baffling required decreases until a point is reached beyond which baffling is detrimental to the mixing action. With very high viscosity material, the baffles have the effect of forming pockets adjacent to the tank wall. Such parts of the mix as are in these pockets, tend to stay there and are not effectively recirculated and intermixed with the rest of the material in the tank. Additionally, the power required to rotate the impeller under such conditions is undesirably large.

From the foregoing, it will be seen that satisfactory mixing with the prior art apparatus, requires different installations for materials of high and low viscosity. Often this necessitates extra installations which cannot be used to capacity. But an even more serious drawback exists in processes that cause the material to undergo a great change in viscosity during the mixing or dissolving treatment. Some examples of such processes are paint pigmentation, the manufacture of clay slurries and asphalt emulsions, and the dissolving of materials used in making rayon, acetate silk, and lacquers, e. g., dissolving xanthate materials in a solution of caustic soda. For such processes, the prior art mixing apparatus can be no more than a compromise which will function efficiently only at an intervening viscosity. The time and the energy required to

carry out the process are increased accordingly.

A general object of the present invention is to provide mixing or dissolving apparatus which functions efficiently with material of either high or low viscosity.

Another object of the invention is to provide mixing or dissolving apparatus which functions efficiently as the mix progressively increases in viscosity.

More specific objects of the invention are to equip mixing or dissolving apparatus with baffles which have diminishing effect as the viscosity of the mix increases, and to provide a suitable method of determining the best placement of such baffles.

Other specific objects are to provide a baffle which has full effect at low viscosity and virtually no effect at high viscosity, and to provide a method of placement for such a baffle.

Various additional objects and advantages will be apparent to those skilled in the art from a consideration of the following disclosure.

In general, the circulation in the tank is along paths outwardly of the impeller toward the side of the tank, along the tank wall in a helical path, inwardly of the tank wall toward the axis of the impeller, and lengthwise of such axis back to the impeller for recirculation. This is a complex path of movement involving vertical and horizontal components of motion. For convenience and clarity the path of flow will be discussed herein-after in terms of the vertical and horizontal components of motion.

Two suitable forms of construction are shown, by way of example, in the accompanying drawings, wherein:

Fig. 1 is a largely diagrammatic vertical section through a two-impeller mixer embodying the present invention, the view being taken approximately on line 1—1 of Fig. 2;

Fig. 2 is a largely diagrammatic plan view of the same;

Fig. 3 is a diagram indicating the horizontal component of the flow in the case of a liquid of low viscosity;

Fig. 4 is a diagram indicating the horizontal component of the flow in the case of a liquid of high viscosity; and

Fig. 5 is a largely diagrammatic vertical section through a single-impeller mixer.

In Figs. 1 and 2 a tank designated as a whole has a cylindrical side wall 1, and has a top flange 2 to receive a cover (not shown). Depending coaxially into the tank is a vertical shaft 3 that is rotated by any suitable source of power 4.

(not shown). Mounted on the shaft are spaced involute impellers 10 and 11 which may be of conventional form but which are preferably of the "tilted" variety disclosed in United States Patent 1,908,002. In a zone above impeller 10 there is affixed to tank wall 7 a series of baffles 12 (four shown). In the zone between impellers 10 and 11 there is affixed to tank wall 7 a second series of baffles 13 (four shown).

10 The baffles 12 and 13 may be mounted with the aid of any suitable means, the drawing merely showing supporting rods 14 to illustrate the mounting in a diagrammatic manner. Each of the baffles 12 and 13 extends in a generally vertical direction and is spaced inwardly from the tank wall 7, as shown in the drawing. Additionally, each of the baffles 12 and 13 is positioned at an angle to the tank radius, with its trailing longitudinal edge *t* farther from the tank wall 20 than its leading edge *l*. Each of baffles 12 is also inclined from bottom to top circumferentially of the tank in the direction of impeller rotation. Baffles 13 are positioned vertically.

25 The action of the baffles in opposing swirling of the liquid is illustrated in Fig. 3. The spiral line 15 indicates the horizontal component of the path which an elemental volume of relatively low viscosity liquid would follow in the absence of baffles. With the baffles present, the liquid 30 moving in the same direction at 16 strikes a baffle (12 or 13) and is projected at 17 toward the axial zone of the tank.

35 As the viscosity of the mix increases, the path 15 becomes a more and more pronounced spiral, with the result that the baffles present less and less effective surface to the spiral flow. Thus the effect of the baffles decreases as the viscosity increases. With very high viscosity the horizontal component of flow without baffles would be 40 as indicated by line 15^a in Fig. 4. It will be apparent that this path is such that the baffles 12 and 13 are positioned edgewise to the flow and hence offer only skin friction resistance.

45 With regard to the vertical component of flow, the tank may be considered as divided into superimposed flow zones, roughly indicated in Fig. 1 by dotted flow lines. Each of the impellers is in a zone of outward flow. Adjacent each side of each zone of outward flow is a zone of flow axially of the tank. And the zones of axial flow merge into zones of inward flow.

50 This vertical component of flow is very effective in promoting the mixing or dissolving, and hence it should be impeded as little as possible. As an elemental volume of liquid moves upwardly (e.g., along circuit *d*) it also moves circumferentially of the tank in the direction of impeller rotation (see Fig. 3). Thus, the resultant path is on an incline, upwardly and circumferentially in the 55 direction of impeller rotation. As the longitudinal axes of baffles 12 are also correspondingly inclined these baffles offer only skin friction resistance to the vertical component of flow.

55 As the flow in circuit *b* baffles 13 should theoretically be circumferentially inclined the same as baffles 12. However, these baffles also handle the downward flow in circuit *c*, for which baffles 13 should theoretically be circumferentially inclined in the opposite direction. As a compromise the longitudinal axes of baffles 13 are 60 positioned vertically; and the variation from the theoretically desirable inclination is small enough to be permissible.

65 The form of the invention shown in Fig. 5 is generally similar in arrangement and action to

the first form of the invention. The shaft 20 carries a single impeller 21, which is positioned near the bottom of tank 22. A series of baffles 23 (three shown) are supported from the tank wall 24. These baffles are spaced from the tank 5 wall, inclined to the tank radius, and have their axes circumferentially inclined, all in correspondence with baffles 12 in Figs. 1 and 2.

70 The spacing of the baffles from the tank wall eliminates pocket formations which tend to trap 10 and localize portions of the mix. Furthermore, such spacing prevents the baffles from interfering with the flow adjacent to the wall, where it has a tendency to be a minimum. In the forms shown in the drawing the baffles do not extend 15 in alignment with the impellers, which leaves a perfectly free flow path from the impeller to the tank wall. With liquids of low viscosity, part of the horizontal flow component passes between the baffles and the tank wall. This produces 20 eddies at the restrictions, and these eddies augment the retarding effect of the baffles and also enhance the mixing action.

25 The range of viscosities to be handled determines the optimum inclinations of the baffle. In determining the placement of the baffles, I prefer to do it by trial. The tank, or a substantial duplicate thereof, is filled with a transparent material of the maximum viscosity to be handled. Dark beads or other suitable objects are also 30 placed in the tank, so that the lines of flow can be seen. A baffle is then temporarily inserted and adjusted into such position that it is edgewise to the path of flow. In this way the optimum inclinations of the baffle, can be predetermined for 35 both the horizontal and vertical components of flow. In an installation which I have used for viscosities up to 60,000 centipoise, the angle alpha in Fig. 3 was 55°. This angle is the angle which the horizontal center line of the baffle makes with 40 the horizontal tank tangent intersected by the center line. The higher the maximum viscosity, the greater the baffle inclinations will be, and vice versa.

45 The amount of space between the baffle and the tank wall which I have found desirable is from one-half inch to one inch, per foot of tank diameter. While the baffles may be given a curved form to correspond exactly with the flow lines at maximum viscosity, they are conveniently made of 50 flat sheet metal and with the proper placement serve adequately. The mounting of the baffles may provide for adjustment of the baffle inclinations after the installation is made, with means to lock the baffles at the desired setting. However, it is usually simpler and more satisfactory to predetermine the baffle placement and use 55 baffle mountings which do not provide for adjustment of the inclinations.

60 In compliance with the patent statutes, I have disclosed the best forms in which I have contemplated applying my invention, but the disclosure should be considered as illustrative, not limiting.

65 What is claimed is:

1. In mixing apparatus of the type in which the mix is circulated by a pair of vertically spaced rotating impellers mounted on a substantially vertical shaft, the improvement which comprises: two series of upwardly extending baffles each adjacent to and spaced from the tank wall, the first series being located above the level of the upper impeller and the second series being located between the levels of the two impellers, the baffles of both series having their deflecting faces 70 75

inclined with respect to the intersecting tank radii, the baffles of the first series being also inclined upwardly and circumferentially in the direction of impeller rotation, and the baffles of the second series being substantially vertical.

- 5 2. In mixing apparatus of the type in which the mix is circulated in a cylindrical tank by an impeller rotating on a substantially vertical axis, the mix flowing outwardly from the impeller and then flowing in an inclined upward path adjacent to the tank wall, the inclination of the path being circumferential of the tank in the direction of impeller rotation; the improvement which

comprises: upwardly extending baffles adjacent to and spaced from the tank wall, the baffles being located along said inclined upward flow path and being themselves inclined upwardly and circumferentially in the direction of impeller rotation, said baffle inclination being approximately equal to said inclination of the flow path, and the baffles also being inclined with respect to the intersecting tank radii and having the trailing edges of the baffles closer to the center of the 10 tank than the leading edges of the baffles.

inclined with respect to the intersecting tank radii, the baffles of the first series being also inclined upwardly and circumferentially in the direction of impeller rotation, and the baffles of the second series being substantially vertical.

- 5 2. In mixing apparatus of the type in which the mix is circulated in a cylindrical tank by an impeller rotating on a substantially vertical axis, the mix flowing outwardly from the impeller and then flowing in an inclined upward path adjacent to the tank wall, the inclination of the path being circumferential of the tank in the direction of impeller rotation; the improvement which

comprises: upwardly extending baffles adjacent to and spaced from the tank wall, the baffles being located along said inclined upward flow path and being themselves inclined upwardly and circumferentially in the direction of impeller rotation, said baffle inclination being approximately equal to said inclination of the flow path, and the baffles also being inclined with respect to the intersecting tank radii and having the trailing edges of the baffles closer to the center of the 10 tank than the leading edges of the baffles.
